Primary Examiner — Philip S Hyder

(74) Attorney, Agent, or Firm — CRAMER PATENT & DESIGN, PLLC; Aaron R. Cramer

(57) **CLAIM**

The ornamental design for a drywall spike, as shown and described.

DESCRIPTION

FIG. 1 is a perspective top front right view of a drywall spike, showing my new design;

FIG. 2 is a perspective top rear left view thereof;

FIG. 3 is a front elevation view thereof;

FIG. 4 is a rear elevation view thereof;

FIG. 5 is a right elevation view thereof;

FIG. 6 is a left elevation view thereof; and,

FIG. 7 is a top plan view thereof, wherein a bottom plan view is an identical image thereof.

1 Claim, 5 Drawing Sheets
